(Cl. D44—15)

To all whom it may concern:

Be it known that I, Harris Brin, a citizen of the United States, residing in Fort Worth, in the county of Tarrant and State of Texas, have invented a new, original, and ornamental Design for a Baby Food Server Unit, of which the following is a specification, reference being had to the accompanying drawing, forming a part thereof.

Figure 1 is a perspective view of a baby food server unit, showing my new design which is comprised of a base and three separate containers assembled as shown.

Figure 2 is a plan view of the baby food server unit illustrated in Figure 1.

Figure 3 is an end view.

I claim:

The ornamental design for a baby food server unit, substantially as shown and described.

HARRIS BRIN.
